TYPEWRITING MACHINE

Alfred G. F. Kurowski, Brooklyn, N. Y., assignor
to Underwood Elliott Fisher Company, New
York, N. Y., a corporation of Delaware

Application November 23, 1936, Serial No. 112,269

29 Claims. (Cl. 197—63)

This invention relates to typewriters, and more especially to margin-stops.

It is a feature of the invention to provide a pair of concurrently adjustable margin-stops intersected by stops on the carriage and connected with a pair of parallel racks, one with each, the racks being operatively connected with a common intermediate engaging pinion which has a definite fixed position on the frame of a typewriter and is associated with parallel guides so that the movement of a margin-stop in one direction effects the simultaneous and equidistant movement of the other margin-stop in the opposite direction, one of the margin-stops having a part movable to actuate a signal and a key-lock, when engaged by a part on the carriage; the pinion may be fixed centrally of the frame of the typewriter; the movable part may be the lower part of the margin-stop and may be depressed by an extension fixed on the carriage; the right margin-stop may be adjustably set on the frame by a latch so that its movement simultaneously moves the other margin-stop, and in an alternate form both margin-stops are freely adjustable, the pinion being surmounted by a knurled button and rotatable therewith and being settable in any rotatable position by a latch; the latching detent may be released by an accessible lever; and the part that operates the signal may also operate the key-lock. Pointers on each margin-stop may indicate the adjusted positions on a scale.

Other features and advantages will hereinafter appear.

In the accompanying drawings,

Figure 1 is a perspective view with some parts cut away.

Figure 2 is a cross-section through the left or signal-operating margin-stop.

Figure 3 is a plan view of the letter-space scale.

Figure 4 is a plan view with the scale and actuating knob cut away to show the margin-stop adjusting racks, looking in the direction of the arrows 4—4 of Figure 5.

Figure 5 is a part sectional view looking in the direction of the arrows 5—5 of Figure 4.

Figure 6 is a part sectional view looking in the direction of the arrows 6—6 of Figure 4.

Figure 7 is a view similar to Figure 4, but showing a modification.

Figure 8 is a diagrammatic view showing the carriage approaching the bell and locking positions.

Figure 9 is a diagrammatic view showing the carriage banked against the right margin-stop at the beginning of a line.

Figure 10 is a central part section through the middle of Figure 7 and looking toward the left.

Figure 11 is an enlarged perspective view of a modification showing the adjusting button and its detent shown in Figure 7.

Referring to the drawings, a typewriter-frame 20 supports a reciprocating carriage 21, on which a platen 22 is rotatably mounted and supports a work-sheet 23 upon which types 24 imprint. A wheel 25 supports the front of the carriage 21 on a notched rail 26. A letter-space scale 27 is secured by screws 28 to a scale-bar 30. Screws 31 at either end of the scale-bar 30 secure the scale-bar 30 to the frame 20. A scale-pointer 32 is mounted on the carriage 21 over the wheel 25. A stop 33 projects forwardly from the carriage 21 to the left of the wheel 25 and is so positioned that it engages by overriding a depressible piece 34 which rests on a cross-bar 35 which has at either end a forwardly projecting arm 36 pivotally mounted on a rod 37 which connects the two sides of the frame 20. A restoring spring 38 is secured to the frame 20 and engages one of the arms 36 and tends to hold the cross-bar 35 in an upward position in engagement with a pin 47 projecting inwardly from the inside of one side of the frame 20. The depressible piece 34 has a usual signal-operating cam 39 and a usual line-lock cam 40 as well as the final stop 41 and is secured to a left margin-stop 42 which is slidably mounted on the rod 37. The depressible piece 34 is adjustable with the margin-stop 42 in the direction of movement of the carriage in either direction. An arm 43 is secured by screw 44 to the bottom of the margin-stop 42 and projects underneath the cross-bar 35 so that the lower part of the pivoted margin-stop 42 and the cross-bar 35 must move upwardly and downwardly together. A pointer 45 shown in Figure 3 in relationship to the scale 27 is secured on the front vertical face of the margin-stop 42 by screws 46. An arm 50 is secured by screws 51 to the rear vertical wall of the cross-bar 35 and depends downwardly near the inner wall of the left side of the frame 20 and also has at its lower end, as is well known in the art, as shown in Figure 1, an arm 52 depending therefrom and pivoted thereon by a pin 53. Transversely of the lower end of the arm 52 on the side toward the frame wall is a transverse pin 54 and on the inner side a camming lug 55 which rests on the upper edge of a lever 56 which is formed with a camming surface for actuating the bell-lever 58. A leftwardly turned end 49 of the arm 52 acts as a stop against the rear vertical wall of the arm 55.

50 to prevent yielding of the arm 52 on the pin 53 in one direction. A ball 57 is carried on the rear end of the arm 56 pivoted on the inside of the frame 20 in a manner well known in the art so that when the carriage-stop 33 engages the right cam 39 of the cross-piece 34 the bell 58 is struck by the ball 57 to signal the approach of the end of a line. An opposite arm 59 normally held in a rearward position, as shown in Figure 1, by a spring 60 secured to it and to the frame 20 is fast on a rock-shaft 61 which supports a second upstanding arm 62 on which is supported a cross-rod 63 which is adapted to move forwardly and to underlie a hook 64 supported on each key-lever 65. This cross-rod forms a key-lock 63 which is actuated by the movement of the carriage-stop 33 further to the left on the cross-piece 34, thereby camming it down so as to swing the arm 50 which causes the pin 54 to engage the rear vertical wall of the upstanding arm 53 and push it forward together with the rod 63 into the locking position of the latter under the hook 64. After the carriage-stop 33 has engaged the stop 41, the margin may be released for a few more letter spaces by pushing rearwardly a plunger 48 which engages the arm 50 in a manner well known in the art.

Mounted on the right side of the wheel 25 on the carriage 21 is an upwardly movable stop 66 formed by a forward right-angled bend from the left end of a lever 67 mounted on a pivot-screw 68 secured to the carriage 21. A spring 69 is secured to the top of lever 67 and on the left side of the pivot-screw 68 and tends to hold the carriage-stop 66 down in its operative position. The other end of the lever 67 projects through a slot in the end of the carriage to form a releasing arm 70 which may be depressed sufficiently to raise the carriage-stop 66 up out of engaging position with a right-hand adjustable margin-stop 71. This margin-stop 71 is a rearward projection from a body-portion 72 which is slidably mounted on the rod 37. The pointer 73 is secured to the front vertical face of the body-portion 72 by screws 74 and overlies the scale 27 as shown in Figure 3. The rail 26 is provided on the front edge with teeth 75 as shown in Figures 4 and 6, which are engaged by teeth 89 on the rear edge of an arm 76 which is mounted by means of a vertical pivot-screw 77 on the body-portion 72. A spring 78 is mounted in a socket in the inner wall of the body-portion 72 and in an opposite socket in the inner wall of the arm 76 to the right of the pivot-screw 77 and therefore tends to keep the arm 76 in engagement with the teeth 75 on the rod 26. A finger-piece 79 may extend forwardly from the lower part of the pivoted arm 76 and to the left of this finger-piece 79 is mounted a thumb-piece 80 which may be formed with and extended downwardly from the body of the pointer 73. It is clear that the pressure of the finger and thumb on the finger-piece 79 and the thumb-piece 80 respectively removes the arm 76 from engagement with the tooth 75 so that the margin-stop 71 may be adjusted either to the right or to the left along the rod 37. Near the left side of the margin-stop 42 is formed a front slot 81 which secures a bracket 82 slidably on the rod 37. The bracket 82 has a laterally extending and forwardly inclined flat arm 83 to the upper surface of which is secured, by means of screws 84 passed through the lower inner wall of the arm 63, an elongated arm 85 the rear edge of which is notched to form a rack 86. By reference to Figure 5 it is seen

that the margin-stop at the left is formed of two parts pivotally mounted on the rod 37 for movement toward and away from each other, a construction which permits the elongated arm 85 and the bracket 82 to remain in the upper position and the lower portion 42 of the margin-stop to be depressed with the connected depressible piece 34. As shown in Figure 6, a pin 87 is mounted on the top flat surface of the body-portion 72 of the right-margin-stop 71 and a bracket 88, which is of a general U-shape except that the upper part is inclined forwardly and downwardly, has a circular aperture in the lower portion adapted to fit over the pin 87. Screws 90 are passed through the upper portion and 10 into an arm 91 which has on its forward edge notched teeth forming a rack 92 which is slideable to the left or right concurrently with the margin-stop 71. A guide-plate 93 has an upturned front wall 94 and a parallel upturned 20 rear wall 95 and is secured by two screws 96 to the lower wall of the scale-bar 30 from which the plate 93 is spaced by means of studs 97. A centrally positioned pivot-screw 98 is secured to the lower wall of the scale-bar 30 and mounts a 25 cylindrical spacing collar 99 on which is rotatably mounted a pinion 100. The teeth of the pinion 100 and the toothed racks 86, 92 are secured in constant engagement by the guide-walls 94 and 95. The guide-plate 93 may be centrally positioned in respect to the scale-plate 30 as shown in Figure 3. The scale 27 may have at the top the usual letter-space indexing and at the bottom a separate scale in which zero is at the center and numerals one to eight inclusive on either side indicate the settings by means of the carriage-stop pointers 45 and 73 of their respective margin-stops. It is clear that, in the construction which has been described, if the pinion 100 is fixed centrally of the machine and 40 the arm 76 is released from the teeth 75 by grasping the finger-piece 79 and thumb-piece 80 and the margin-stop 71 is thereupon slid along the rod 37 in either direction, then the margin-stop 45 42 is concurrently and equidistantly moved in an opposite direction, so that if the right margin-stop is set a given number of letter spaces to one side of the center the other margin-stop is also set the same number of letter spaces away from the center. It is also clear that the arm 85 and 50 the bracket 82 are supported by the guide 93 so that they do not tilt downwardly when the carriage-stop 33 depresses the part 42 of the margin-stop, or, in other words, the lower part of the left margin-stop is depressible with reference to the upper part of the margin-stop. It is also clear that the lower surface of the scale-bar 30 holds the arms 85 and 91 in assembled position on the guide-plate 93 and by removing the screws 34 from the frame 20 access is readily had to the 55 assembly of the pinion 100 and the racks 86 and 92. No latch is required on the left margin-stop 42 to secure it in an adjusted position but the arm 76 when latched with the teeth 75 of the rail 26 latches simultaneously both of the 60 margin-stops against movement along the rail. A downwardly and forwardly extending arm 29 fastened to the front of the carriage 21 lies under the rail 26 and prevents upward movement of the carriage with reference to the rail. In Figures 70 7, 10, and 11, a modification is shown in which the central portion of the scale 27 is omitted and the two parts are secured to the scale-bar 30 by screws 105 at the inner ends of each part. The guide-plate 93 has a central aperture to receive 105

the head of a screw 106 which holds the pinion 100 tight against the under flat surface of the scale-bar 30 and therefore in mesh with the racks on the arms 85 and 91. The screw 106 fits in the lower end of a post 107 which is square in cross-section and the head of the screw secures the pinion 100 on this post. Above the pinion 100 is mounted a cylindrical bearing 108 rotatable together with the post 107 in a central aperture in the scale-bar 30. Above the scale-bar 30 and rotatable on the upper surface thereof with the post 107 is a toothed wheel 109 and overlying the latter is a knurled button 110 which is held on the top of the post 107 by a screw 111. A yieldable detent spring 112 is mounted on the scale-bar 30 and engages one side of the toothed wheel 109. A lever-arm 113 which has a forward upstanding finger-piece 114 is oscillatable on a pin 115 which is mounted on the top of the scale-bar 30. The opposite end of the lever-arm 113 has a locking tooth 116 which locks the toothed wheel 109 by engaging in one of the notches between the teeth. A suitable spring 117 has one end fast in a hole in the top of the scale-bar 30 and the other end overlying the lever 113, the spring being turned about the post 115 on which the lever 113 is pivoted in such manner that the spring tends to hold the tooth 116 in locking position. It is now clear that if the finger-piece 114 is moved toward the right to release the locking tooth 116, the knurled button 110 may be rotated in either direction and that concurrently both margin-stops 42 and 71 are moved equidistantly in opposite directions along the rod 37 and that when the finger-piece 114 is released the detent-tooth 116 forthwith locks the margin-stops in the adjusted position. As is shown in Figure 7, in the modification it is not necessary to have the teeth 75 on the rail 26 nor is it necessary to have the toothed arm 76 mounted on the body 72 of the margin-stop 71 thereby simplifying the construction of the right-hand margin-stop.

Variations may be resorted to within the scope of the invention, and portions of the improvements may be used without others.

Having thus described my invention, I claim:

1. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop connected with said second rack, and a pinion fixed on the frame intermediate said racks and connected with said racks, said second margin-stop being adjustably fixed on the frame, whereby the adjustment of said second margin-stop simultaneously and concurrently slidably moves the first margin-stop on said rod.

2. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which

swings upwardly and downwardly on the rod, a signaling device, means connected with said swinging part for operating said signaling device, a second rack in parallel with said first rack, a second margin-stop connected with said second rack, and a pinion fixed on the frame intermediate said racks and positioned centrally of said margin-stops, said second margin-stop being adjustably fixed on the frame, whereby adjustment of said second margin-stop simultaneously and concurrently slidably moves the first margin-stop a distance from the center equal to that of the second margin-stop.

3. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop connected with said second rack, and a pinion fixed on the frame intermediate said racks and positioned centrally of said margin-stops, said second margin-stop being adjustably fixed on the frame, whereby adjustment of said second margin-stop simultaneously and concurrently slidably moves the first margin-stop a distance from the center equal to that of the second margin-stop.

4. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop mounted on said rod and connected with said second rack, and a pinion fixed on the frame intermediate said margin-stops whereby said margin-stops are simultaneously and concurrently adjustable.

5. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop mounted on said rod and connected with said second rack, and a pinion fixed on the frame intermediate and centrally of said margin-stops whereby said margin-stops are simultaneously and concurrently adjustable.

6. In a typewriter, in combination, a reciprocating carriage, a stop engaging member thereon, a frame, a rod mounted in the frame in parallel with the direction of the reciprocation of the car-

riage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop mounted on said rod and connected with said second rack, a pinion fixed on the frame intermediate said margin-stops whereby said margin-stops are simultaneously and concurrently adjustable, and means for rotating said pinion.

7. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop mounted on said rod and connected with said second rack, a pinion fixed on the frame intermediate said margin-stops whereby said margin-stops are simultaneously and concurrently adjustable, means for rotating said pinion, and a latch for securing said pinion in rotatable adjustment.

8. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop mounted on said rod and connected with said second rack, a pinion fixed on the frame intermediate said margin-stops whereby said margin-stops are simultaneously and concurrently adjustable, and guides for said racks adjacent said pinion.

9. In a typewriter, in combination, a reciprocating carriage, a stop engaging member thereon, a frame, a rod mounted in the frame in parallel with the direction of the reciprocation of the carriage, a margin-stop mounted on and slideable on said rod, a rack for sliding said margin-stop, said margin-stop having two parts, one of which is fixed to said rack, and the other of which swings upwardly and downwardly on the rod, a signaling device, means connected with said swinging part for operating said signaling device, a second rack in parallel with said first rack, a second margin-stop connected with said second rack, a pinion rotatably mounted in fixed position on the frame intermediate said margin-stops and in mesh with said racks whereby said margin-stops are simultaneously and concurrently adjustable, guides for said racks, and a knob for rotating the pinion.

10. In a typewriter, in combination, a reciprocating carriage, a stop engaging member thereon, a frame, two margin-stops mounted on the frame for adjustment in the direction of the carriage movement, two parallel racks, one connected with each margin-stop, guides for said racks, a pinion

intermediate and operatively engaging said racks, said pinion being pivoted on the frame whereby said margin-stops are adjustable toward and away from each other concurrently, and a single latch for latching both of said margin-stops in their adjusted positions.

11. In a typewriter, in combination, a reciprocating carriage, a stop engaging member thereon, a frame, two margin-stops mounted on the frame for adjustment in the direction of the carriage movement, two parallel racks, one connected with each margin-stop, guides for said racks, a pinion intermediate and operatively engaging said racks and intermediate said margin-stops, said pinion being pivoted on the frame whereby said margin-stops are adjustable toward and away from each other concurrently, and a single latch for latching both said margin-stops in adjusted position.

12. In a typewriter, in combination, a reciprocating carriage, a stop engaging member thereon, a frame, a cross rod in the frame, two margin-stops mounted on the rod for adjustment in the direction of the carriage movement, two parallel racks, one connected with each margin-stop, guides for said racks, a pinion rotatably mounted in fixed position on the frame intermediate and operatively engaging said racks, said pinion being pivoted on the frame whereby said margin-stops are adjustable toward and away from each other concurrently, and a single latch for latching both said margin-stops in their adjusted positions.

13. In a typewriter, in combination, a reciprocating carriage, a stop engaging member thereon, a frame, a rod in the frame, two margin-stops mounted on the rod for adjustment in the direction of the carriage movement, two parallel racks, one connected with each margin-stop, guides for said racks, a pinion rotatably mounted in fixed position on the frame intermediate and operatively engaging said racks, and intermediate said margin-stops, said pinion being pivoted on the frame whereby said margin-stops are adjustable toward and away from each other concurrently, and a single latch for latching both said margin-stops in their adjusted positions.

14. In a typewriter, in combination, a reciprocating carriage, a stop engaging member thereon, a frame, two margin-stops mounted on the frame for adjustment in the direction of the carriage movement, two parallel racks, one connected with each margin-stop, guides for said racks, a pinion intermediate and operatively engaging said racks, said pinion being pivoted on the frame whereby said margin-stops are adjustable toward and away from each other concurrently, a single latch for latching both of said margin-stops in their adjusted positions, pointers on the margin-stops, and a scale on the frame with which said pointers cooperate to indicate the position of said margin-stops.

15. In a typewriter, in combination, a reciprocating carriage, a stop engaging member thereon, a frame, two margin-stops mounted on the frame for adjustment in the direction of the carriage movement, two parallel racks, one connected with each margin-stop, guides for said racks, a pinion intermediate and operatively engaging said racks and having a pivot fixed on the frame, whereby said margin-stops are adjustable toward and away from each other concurrently, and a single latch for latching both of said margin-stops in their adjusted positions.

16. In a typewriter, in combination, a reciprocating carriage, a stop engaging member thereon, a frame, a scale-bar mounted on said frame,

two margin-stops mounted on the frame for adjustment in the direction of the carriage movement, two parallel racks, one connected with each margin-stop, guides for said racks, a pinion 5 intermediate and operatively engaging said racks, said pinion being pivoted on the scale-bar whereby said margin-stops are adjustable toward and away from each other concurrently, and a single latch for latching both of said margin-stops in 10 their adjusted positions.

17. In a typewriter, in combination, a reciprocating carriage, a stop engaging member thereon, a frame, two margin-stops mounted on the frame for adjustment in the direction of the carriage movement, two parallel racks, one connected with each margin-stop, guides for said racks, a pinion intermediate and operatively engaging said racks, a scale-bar on said frame, and a support for said pinion secured to the back 15 of said scale-bar, whereby said margin-stops are adjustable toward and away from each other concurrently.

18. In a typewriter, in combination, a reciprocating carriage, a stop engaging member thereon, a frame, a rod, two margin-stops mounted on the rod for adjustment in the direction of the carriage movement, two parallel racks, one connected with each margin-stop, guides for said racks, a scale-bar mounted on said frame, a pinion 20 engaging said racks, a support for said pinion secured to the back of said scale-bar, and guides for said racks mounted on said support, whereby said margin-stops are adjustable toward and away from each other concurrently.

19. In a typewriter, in combination, a reciprocating carriage, a stop engaging member thereon, a frame, a key, a key-lock, a signaling device, a rod in the frame, a left-hand margin-stop, said margin-stop being slidable on the rod 25 and having two cams, said cams being depressible, a stop on the carriage successively engaging said cams to operate the signaling device and the key-lock, a transverse slot in said margin-stop, a bracket mounted on said rod and in 30 said slot, a rack-arm secured on said bracket, a second margin-stop at the right on said rod, a releasable stop on the carriage engageable with said second margin-stop, a rack-arm secured to 35 said second margin-stop, a scale-bar on the frame, a piece secured on the under side of the scale-bar to support and guide said rack-arms, a pinion supported on said piece between said 40 guides and engaging both of said rack-arms, whereby both margin-stops may be simultaneously and concurrently moved in either direction 45 equidistantly, and a single latch for latching both of said margin-stops.

20. In a typewriter, in combination, a reciprocating carriage, a stop engaging member thereon, a frame, a rod mounted on said frame, a signaling 50 device, a margin-stop slidable on said rod in the direction of carriage movement, said margin-stop being swingable about said rod to actuate said signaling device, a rack pivotally connected to 55 said margin-stop, means for guiding said rack in lineal movement with said margin-stop, and means for releasably locking said rack against movement.

21. In a typewriter, in combination, a reciprocating carriage, a stop engaging member thereon, a frame, a rod mounted on said frame, a key-locking device, a margin-stop slidable on said rod in the direction of carriage movement, said margin-stop being swingable about said rod to operate 60 said key-locking device, a rack pivotally 65

connected to said margin-stop, means for guiding said rack in lineal movement with said margin-stop, and means for releasably locking said rack against movement.

22. In a typewriter, in combination, a reciprocating carriage, a stop engaging member thereon, a frame, a rod mounted on said frame, a signaling and key-locking device, a margin-stop slidable on said rod in the direction of carriage movement, said margin-stop being swingable about 10 said rod to actuate said signaling and key-locking device, a rack pivotally connected to said margin-stop, means for guiding said rack in lineal movement with said margin-stop, a pinion in mesh with said rack, and means for rotating said 15 pinion whereby to adjustably position said margin-stop along said rod.

23. In a typewriter, in combination, a reciprocating carriage, a stop engaging member thereon, a frame, a rod mounted on said frame, a signaling and key-locking device, a margin-stop slidable on said rod in the direction of carriage movement, said margin-stop being swingable about 20 said rod to actuate said signaling and key-locking device, a rack pivotally connected to said 25 margin-stop, means for guiding said rack in lineal movement with said margin-stop, a pinion in mesh with said rack, means for rotating said 30 pinion whereby to adjustably position said margin-stop along said rod, and releasable means for locking said pinion against rotation.

24. In a typewriter, in combination, a frame, a carriage mounted for reciprocating movement relatively to said frame, a stop engaging member thereon, a first margin-stop and a second margin-stop slidable mounted on said frame in the direction of carriage movement, each margin-stop including a rack, a pinion rotatably mounted on said frame and in mesh with said racks whereby a movement of one of said margin-stops is 35 transmitted to effect an equivalent movement of the other margin-stop, and means for releasably fixing said margin-stops in adjusted positions.

25. In a typewriter, in combination, a frame, a carriage mounted for reciprocating movement relatively to said frame, a stop engaging member thereon, a first margin-stop and a second margin-stop slidable mounted on said frame in the direction of carriage movement, each margin-stop including a rack, a pinion rotatably mounted 40 on said frame and in mesh with said racks whereby a movement of one of said margin-stops is transmitted to effect an equivalent movement of the other margin-stop, and means for releasably fixing said margin-stops in adjusted positions, 45 said second margin-stop having a releasable connection with the corresponding rack to permit 50 independent movement of said first margin-stop.

26. In a typewriter, in combination, a frame, a carriage mounted for reciprocating movement 55 relatively to said frame, a stop engaging member thereon, a first margin-stop and a second margin-stop slidable mounted on said frame in the direction of carriage movement, each margin-stop including a rack, a pinion rotatably mounted 60 on said frame and in mesh with said racks, means for yieldably resisting rotation of said pinion, and means for rotating said pinion whereby to move both of said margin-stops 65 simultaneously and equidistantly.

27. In a typewriter, in combination, a frame, a carriage mounted for reciprocating movement relatively to said frame, a stop engaging member thereon, a first margin-stop and a second margin-stop slidable mounted on said frame in the 70 75

- direction of carriage movement, each margin-stop including a rack, a pinion rotatably mounted on said frame and in mesh with said racks whereby a movement of one of said margin-stops 5 is transmitted to effect an equivalent movement of the other margin-stop, a toothed wheel rotatable with said pinion, and a resilient detent engaging said wheel to yieldably hold both of said margin-stops against movement.
- 10 28. In a typewriter, in combination, a frame, a carriage mounted for reciprocating movement relatively to said frame, a stop engaging member thereon, a first margin-stop and a second margin-stop slidably mounted on said frame in the 15 direction of carriage movement, each margin-stop including a rack, a pinion rotatably mounted on said frame and in mesh with said racks whereby a movement of one of said margin-stops is transmitted to effect an equivalent movement of 20 the other margin-stop, a toothed wheel rotatable

with said pinion, and a spring-pressed lever having a detent engaging a tooth of said wheel to releasably lock said pinion against rotation.

29. In a typewriter, in combination, a frame, a carriage mounted for reciprocating movement relatively to said frame, a stop engaging member thereon, a first margin-stop and a second margin-stop slidably mounted on said frame in the direction of carriage movement, each margin-stop including a rack, a pinion rotatably mounted 5 on said frame and in mesh with said racks whereby a movement of one of said margin-stops is transmitted to effect an equivalent movement of the other margin-stop, a toothed wheel rotatable with said pinion, a resilient detent engaging said 15 wheel, and a spring-pressed lever having a detent engaging said wheel to releasably lock said pinion against rotation.
